(57) **CLAIM**

The ornamental design for display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a portion of a display screen showing a first embodiment of my new design;

FIG. 2 is a front view of a portion of a display screen showing a second embodiment of my new design;

FIG. 3 is a front view of a display screen or portion thereof showing a third embodiment of my new design; and,

FIG. 4 is a front view of a display screen or portion thereof showing a fourth embodiment of my new design.

The peripheral broken lines represent a display screen or portion thereof and form no part of the claimed design. The broken lines within the peripheral broken lines, with the exception of the wavy broken lines, represent portions of the graphical user interface which form no part of the claimed design. The wavy broken lines represent a symbolic break in horizontal dimension and form no part of the claimed design. The appearance of any portion of the graphical user interface between the wavy broken lines forms no part of the claimed design.
